UNITED STATES PATENT OFFICE.

ROBERT H. ROGERS, OF SCHENECTADY, NEW YORK, ASSIGNOR TO GENERAL ELECTRIC COMPANY, A CORPORATION OF NEW YORK.

DYNAMO-ELECTRIC MACHINE.

No. 822,304.

Specification of Letters Patent.

Patented June 5, 1906.

Application filed November 30, 1904. Serial No. 234,831.

To all whom it may concern:

Be it known that I, ROBERT H. ROGERS, a citizen of the United States, residing at Schenectady, county of Schenectady, State 5 of New York, have invented certain new and useful Improvements in Dynamo-Electric Machines, of which the following is a specification.

My present invention relates generally to 10 a suitable construction whereby a variable voltage less than its normal voltage may be obtained from a direct-current generator without interfering with the proper operation of the generator and the supply of current 15 of the normal voltage therefrom.

In particular, my invention has for its object the supplying of the necessary current by the generator for electrically igniting the charge of an internal-combustion engine, 20 such as the ordinary gas-engine driving the generator.

The various features of novelty which characterize my invention are pointed out with particularity in the claims annexed to 25 and forming a part of this specification.

For a better understanding of my invention, however, reference may be had to the accompanying drawings and description, in which I have illustrated and described one 30 embodiment of my invention.

Of the drawings, Figure 1 is an elevation of a dynamo-electric machine equipped with my invention. Fig. 2 is an elevation, on a larger scale, showing the auxiliary brush-holder. Fig. 3 is a section at right angles to Fig. 2, taken to show both the supporting-stud and the auxiliary brush-holders of the generator shown in Fig. 1. Fig. 4 is a plan view showing a portion of the commutator 40 and brushes of the generator shown in Fig. 1, and Fig. 5 is a diagrammatic representation showing the external connections for supplying the ignition-current to the engine.

Referring to the drawings, 1 represents the 45 field-ring of a dynamo-electric machine the armature 2 of which is carried by a shaft 3, journaled in suitable brackets or pillow-blocks 4. The commutator 5 of the machine is mounted on the shaft 3 in the usual 50 manner. The particular machine illustrated in the drawings is a six-pole direct-current generator. The main brushes 6 are carried by suitable brush-holders 7, clamped to studs 8, which extend parallel to the arma-

ture-shaft and are supported in the usual 55 manner.

In the particular construction which I have illustrated one of the brush-holder studs 8 is shortened, as is clearly shown in Fig. 4. To the end of the shortened stud I have secured a trough-shaped member 10 by a pair 60 of clamping-screws 11, tapped into the end of the stud. The screws 11 pass through apertures formed for the purpose in a portion 12 of the member 10, which is parallel 65 to the end of the stud 8. Insulating-washers 13 and an insulating-bushing 14 serve to insulate the member 10, which is of metal, from the stud to which it is supported by the screws 11. A terminal clip 15 may be secured in place by one of the clamping-screws 11, as shown in Fig. 2.

An outer portion 16 of the trough-shaped member 10, parallel to the portion 12, is formed with a slot 17, which extends substantially parallel to the adjacent portion of the commutator. An auxiliary brush-holder 18 is adjustably secured to the portion 16 of the member 10 by a bolt 19 passing through the slot 17 with its head resting against the 80 inner surface of the portion 16 and through a passage formed for the purpose in the brush-holder. The head of the bolt 19 bears against the inner surface of the portion 16, and a clamping-nut 20 is threaded on the outer end 85 of the bolt. As shown, the brush-holder 18 is formed with a guide-rib 21, which enters the slot 17.

In the particular form of auxiliary brush-holder illustrated a carbon brush 22, which 90 may be cylindrical in form, slides in a chamber 23, formed for the purpose in the brush-holder 18. A suitable helical spring 24, located in the chamber 23 above the brush 22, serves to force the brush against the commutator with the proper pressure. A terminal clip 25 may be clamped against the brush-holder 18 by the clamping-nut 20, as shown. 95

Referring to the diagram shown in Fig. 5, 100 30 represents an internal-combustion engine, such as a gas-engine, which may be directly connected to the generator shown in Fig. 1. 31 and 32 represent the terminals of the ignition device within the engine, (not shown,) which may be of any well-known form. Conductors 33 and 34 connect the terminals 31 and 32 to any suitable form of sparking coil 105 35. The conductor 36 connects one of the

terminals of the direct-current energizing-winding of the sparking coil 35 to the clip 25, which is electrically connected to the auxiliary brush 22. Similarly, a conductor 37 connects the other terminal of the direct-current winding of the sparking coil to the clip 15, and thereby to the main brush 6, mounted on the stud to which the auxiliary brush is secured.

10 It will be readily understood that in the operation of the generator the potential between the lines 36 and 37 will be less than the working potential between adjacent brushes 6 of opposite polarity and that the 15 potential difference between the lines 36 and 37 may be readily adjusted by varying the position of the brush-holder with reference to the slotted support 10, thus varying the angular distance between points on the commutator-surface engaged by the auxiliary brush 22 and the main brush supported from the same stud 8. This construction forms a 20 simple and extremely reliable means for supplying the energizing-circuit of the sparking coil 35 with suitable current.

25 In order to supply the sparking coil 35 with energy-current to start the engine, I may provide an auxiliary source of current, such as a storage battery, which may be connected to the lines 36 and 37 at starting by a suitable switch mechanism 38.

In the construction hereinbefore described and illustrated I dispense with one of the brushes and holders normally found on the 35 brush-holder stud 8, which is shortened for the purpose of supporting the auxiliary brush-holder. This is in general satisfactory, as with machines of this type the elimination of one brush-holder usually produces no 40 appreciable difference in the operation of the machine, particularly as the number of brush-holders mounted on one stud in machines of this character is usually four, five, or six instead of two, as I have shown in the drawings.

45 It will be obvious, however, that my auxiliary adjustable brush-holder can be supported in many different ways, and I do not intend that my invention shall be limited to 50 the exact construction shown and described more than is made necessary by the state of the art.

What I claim as new, and desire to secure by Letters Patent of the United States, is—

55 1. In combination, a direct-current generator, an internal-combustion engine for

driving the generator, a sparking coil for the engine, and means for energizing the sparking coil comprising a main brush of the generator and an auxiliary brush adjustable angularly about the commutator of the generator to vary the voltage between the brushes and connections from said brushes to said sparking coil.

2. In a dynamo-electric machine, a commutator, a brush-holder stud, a main brush-holder secured to said stud, an auxiliary brush-holder, brushes in each of said brush-holders, and means for adjustably securing said auxiliary brush-holder to said stud so that said auxiliary brush-holder may be moved bodily about the commutator to vary the angle of arc between the brushes.

3. In a dynamo-electric machine, a brush-holder stud, a main brush-holder secured thereto, a member clamped to the end of said stud, and an auxiliary brush-holder adjustably secured thereto.

4. In a dynamo-electric machine, a main brush-holder, supporting mechanism therefor, and an auxiliary brush-holder secured to said supporting mechanism and angularly adjustable about the co-operating commutator to vary the angle of arc between the brush-holders.

5. In a dynamo-electric machine, a commutator, a brush-holder stud, a main brush secured thereto and engaging said commutator, an auxiliary brush also secured to said stud, and engaging said commutator, and means for adjusting said auxiliary brush about the commutator to vary the angle of arc between the brushes.

6. In combination, a direct-current generator, an internal-combustion engine for driving the generator, and igniting means therefor comprising a main brush of the generator and an auxiliary brush adjustable angularly about the commutator to vary the voltage between the brushes.

7. In a dynamo-electric machine, a brush-holder stud, a brush-holder secured thereto, a member secured to but insulated from the end of said brush-holder stud, and an auxiliary brush-holder secured to said member by a bolt-and-slot connection.

In witness whereof I have hereunto set my hand this 29th day of November, 1904.

ROBERT H. ROGERS.
